UNITED STATES PATENT OFFICE.

GEORGE W. PACKER, OF CHICAGO, ILLINOIS.

MACHINE FOR GRINDING SURFACES OF METALS.

SPECIFICATION forming part of Letters Patent No. 633,895, dated September 26, 1899.

Application filed May 20, 1899. Serial No. 717,576. (No model.)

To all whom it may concern:

Be it known that I, GEORGE W. PACKER, a citizen of the United States, residing at Chicago, in the county of Cook and State of Illinois, have invented certain new and useful Improvements in Machines for Grinding Surfaces of Metals; and I do hereby declare the following to be a full, clear, and exact description of the invention, such as will enable others skilled in the art to which it appertains to make and use the same.

Figure 1 is a plan view of my machine; Fig. 2, a side elevation; Fig. 3, an end elevation; Fig. 4, a sectional view of feeding device. Fig. 5 is a side elevation of that portion of the machine having to do more particularly with feeding and grinding the sections of cutters of harvesting-machines. Fig. 6 is a perspective view of a portion of the cross-carriage. Fig. 7 is a plan view of the section-feeding devices, and Fig. 8 is a front elevation of the said section-feeding devices. Figs. 9 and 10 show details of the cross-carriage. Figs. 11, 12, 13, and 14 are details of the chuck and carriage. Figs. 15, 16, 17, and 18 are details of the universal support for the blank. Fig. 19 is a detail of the arm for holding the blanks in the chute. Fig. 20 is a detail of the plate secured to the side of the chute and its connected parts. Fig. 21 shows in detail the means for roughing the surface of the grinding-wheel.

The object of my invention is to provide a machine that shall automatically accomplish the work of grinding the surfaces of parts cut from sheet metal that may be placed therein; and its nature consists in providing a feeding-hopper into which the parts to be ground may be stood, in means for moving the said parts to position to be taken by a carrier and moved across the surface of a grinding-stone, and in providing various devices for accomplishing the work in the most perfect manner.

The machine is shown as particularly adapted to the grinding of sickle-sections for harvesting machinery.

In the drawings, A is a discoidal grinding-stone hollowed out at its center, as shown in dotted lines, across the face of which the sections are moved by a cross-carriage B, a chuck in which takes them from the hopper C and

moves them forth and back over the face of the stone. The cross-carriage B moves on guideways supported upon the carriage D, 55 which is adjustable in such a manner that the said carriage may follow up the stone as the latter wears away. The carriage is moved by a crank formed upon the shaft E. All of these parts are suitably mounted upon a 60 strong frame F.

The construction and operation may best be made clear by referring to the various parts in detail and then describing their co-operations whereby the results are produced. 65

Mounted upon the main frame F are the pillow-blocks f and f', in which is journaled the shaft f², carrying the face-plate a, to which the grinding-stone A is firmly secured. Upon the shaft is a suitable pulley f³, rotated by 70 a belt f⁴. Upon the shaft is also the small pulley f⁵. Upon a counter-shaft G, Fig. 3, immediately below the shaft E is the pulley g, around which and the pulley f⁵ is thrown the belt g'. Upon the counter-shaft G is the 75 pinion g², adapted to mesh into the gear e upon the shaft E. Upon the latter shaft is a crank-wrist e', secured in the disk e². Extending from this wrist to the cross-carriage is the pitman e⁸, pivoted at e⁴. The pitman 80 at each end is secured to the wrists by means of universal joints, so as to have an abundance of freedom of movement. By movement of the shaft f² it is thus seen that the grinding-stone and the cross-carriage are 85 given the desired movements relative to each other.

As stated, the cross-carriage is supported upon the main carriage D and by the latter is moved to compensate for the wearing away 90 of the grinding-stone. In order that it may so move, the gear e is keyed to the grooved shaft in such a manner that the shaft is free to slide therethrough. The main carriage D is supported upon the frame F and guided by 95 the racks d and d', suitably secured to the latter. Upon the shaft d² are keyed the pinions d³ and d⁴. Upon the end of the shaft d² is secured by ratchet h and upon the lever H a pawl h', and also the adjustable weight h². 100 The purpose of the weighted lever is to move the carriage D toward the grinding-stone and maintain it there under yielding pressure. After the stone has become worn it is neces-

sary, of course, to raise the lever H and adjust the pawl h' to a new tooth of the ratchet.

As there is an interval, for reasons soon to be explained, when there is no section being ground, the main carriage D would be free to move toward the stone were not means provided for preventing the same. Such means consist in the conical roller I, supported upon a stationary pin held in the bracket i upon the carriage D.

As a certain degree of roughness is required on stones for this purpose, a many-toothed roller K (see Fig. 21) is journaled in a support pivoted upon the cross-carriage. (See Figs. 1, 2, 3, and 21.) Horizontally through an upreaching part of the cross-carriage is a hole k, (see Fig. 5,) through which passes the pin k', Fig. 21. The toothed roller K and its connected parts are omitted from Fig. 5 to avoid complicating the drawings and to show parts beyond. This pin serves as a pivot for the framework k². Upon the pin k³ are several toothed disks, which constitute what may be termed the "roller" K. It is of disks in order that it may be more easily manufactured, and also that the parts may rotate at different rates of speed, the said rates depending upon the radial distance from the axis of the grinding-stone. Across the upper part of the frame k² is the pin k⁴, suitably supported, and to this is connected the screw-rod k⁵. Surrounding the screw k⁵, Fig. 21, however, is the doubly-flanged sleeve k⁶, which passes through the slot l⁷ in the upwardly-directed projection l⁴, having any suitable means for rotating it—as, for instance, a hand-wheel k⁷, as shown. The flanges upon the sleeve k⁶ prevent the latter from moving longitudinally. By turning the hand-wheel the roller K may be moved to position to act upon the wheel and give the desired roughness by the points pecking into it.

The devices for feeding the sickle-sections or whatever parts the machine is adapted to grind are shown in the various detailed figures.

The cross-carriage may be better understood by referring to Figs. 6, 7, and 8. It consists, preferably, of a single casting having certain parts secured to it. In the perspective view Fig. 6, L is the main portion of the cross-carriage. This rests upon the main carriage at D, where suitable guideways d⁷ and d⁸ are provided. In order to reduce friction to the minimum, the cross-carriage is provided with the rollers l¹¹. Upon the cross-carriage are the lugs l' and l''. Between these the end of the pitman e⁴ is secured by a suitable pin l², upon which it may oscillate. The rotation of the crank e', it will thus be seen, gives the cross-carriage the necessary reciprocating movement to carry the sections held by its chuck across the face of the grinding-stone. In order to hold the cross-carriage down, a roller l⁵ is secured thereto, adapted to run under a guide m on the main carriage

D, as shown in Figs. 5 and 10. In order to reduce friction, all of these rollers are provided with antifriction-bearings consisting of rollers, as shown in Fig. 10.

The feeding devices may be best studied in Figs. 1, 2, 4, 5, 6, and 8.

C is a hopper in which the sections are stood, its width being such as to confine the said sections within reasonable limits. The bottom 75 of this trough-like hopper is slotted. Within the trough is adapted to move the feeder c, connected to which and extending through the slot is a stud-bolt c'. To the latter is secured the chain c², which, passing around the 80 rollers c³ and c⁴, is attached to the weight c⁵, which through the instrumentality of the chain and the feeder applies constant pressure to the assembled sections within the trough-like hopper. The feeder is provided with a 85 handle c⁶, by which it can be moved back when the operator wishes to put a new supply of sections in place. Upon the face of the cross-carriage are the ledges p and p', which form a kind of chuck, (see Fig. 6,) which are adapted 90 to grasp a section as the carriage recedes. As the carriage moves forward the section is carried along the face of the stone. The ledges p and p' are the ends of a plate P, bent to form the same, p', as shown in Fig. 11. These pass 95 all the way through the cross-carriage, as shown in section in Fig. 14. This angled plate P is made adjustable by means of the screws p² and p³. (See Figs. 8, 9, 10, and 14 and as shown in detail in Fig. 11.)

As grinding-stones wear away more in some places than others, the surfaces often lack mathematical correctness, and the sickle-sections or other parts cut from sheet metal are often somewhat warped. As absolute uniformity in thickness is not always necessary, but, on the contrary, the production of a perfectly-plain surface being required the part of the cross-carriage which lies behind the section and constitutes a chuck, holding it in position while being ground, is pivotally supported, as will be duly described.

To the main portion of the cross-carriage, against the vertical plane r (shown in the perspective view Fig. 6) is the plate r', Figs. 16 and 9, having as one piece therewith the hemisphere r². This plate is secured by any suitable means to the cross-carriage in the position stated.

R, Fig. 15, is a plate of metal provided with a socket adapted to fit onto the hemisphere r². (Shown in the two views in Fig. 16.) The hole in the hemisphere is threaded and adapted to receive the screw r⁴, (shown in Fig. 18,) which also passes loosely through the eye r⁴ in the plate R, Fig. 15. A spring r⁵ is placed upon the screw merely for the purpose of holding the two parts of what may be called a "ball-and-socket joint" in proper relative position, yet with sufficient freedom that the 130 planes of the two plates which the ball and socket connect may vary relatively.

s is a slot into which the finger *s'* drops when a section is discharged from the hopper *C* into the carriage *B*.

S is a plate of metal, secured to the plate *R*, 5 as shown in Figs. 6 and 17.

The two parts *R* and *S* (shown in Figs. 6, 15, and 17) it will now be understood are pivotally secured to the main portion *L* of the cross-carriage *B*. Thus secured and a section held in the position shown in dotted lines, 10 Fig. 6, the plate *S* when the cross-carriage *B* is moving across the stone may be free to adjust itself so that its plane may conform as nearly as possible to the plane of the grinding-surface of the stone whether the latter be a perfect plane or undulating on account of some portions wearing more easily than others. The method of securing the plate *S*, 15 against which the section rests when being ground, by means of ball-and-socket joint is shown in detail in Fig. 14. The method of securing the rollers to the carriage is shown 20 in Fig. 13, where an oil-tube *t* is provided for suitably lubricating the antifriction-rollers.

25 In the plan view in Fig. 7 is shown a bar *U* beside the trough-like hopper. It is provided with two slots *u*, as shown in Fig. 20, through which screws *u'* pass and secure it to the said hopper. A spring *u²* is secured to the main 30 frame and adapted to press against the part *u³* of this slide. Upon the slide is the plate *u⁴*, having the right-angled end *u⁵* and the inclined end *u⁶*.

Turning now to Fig. 2, it will be seen that 35 as the carriage moves a section forward it must pass the plate *u⁴*, which it freely does because of the fact that the edge *u⁶*, which it first reaches, is beveled. The spring yielding, as it does, permits the section to pass 40 freely; but upon the return of the cross-carriage the section is forced against the right-angled edge *u⁵* of the plate and pushed out of the recess in the cross-carriage which sustains the section during the operation of grinding and drops away. The ledge *p* (shown in 45 Fig. 6) is (see Fig. 4) immediately below the section next to be taken, (marked *s²*). To a lug projecting from the trough-like hopper is pivoted the finger *s'*, adapted to press against the 50 column of sections at intervals and force them backward. Its movement for the purpose is accomplished by the plate *b'* upon the cross-carriage having the incline *b²*. As shown in Fig. 4, this finger presses against the 55 plate next to be taken. As the cross-carriage moves the ledges *p* and *p'*, sustaining the section, move it out of position in the hopper toward the grinding-stone. Immediately after it has passed entirely out of the hopper 60 the incline *b²* moves behind the finger *s'* and forces the column of sections away. The working end of this finger is in such position as to press upon the sections about their middle and keep them from falling out of place. 65 The vertical position of this finger is shown in Fig. 5.

In order to press the sections being operated upon elastically against the grinding-stone, a guide *M*, Fig. 7, is provided, against which the roller at the back of the cross-carriage moves. This guide is elastically held in position by the springs *m'* and *m*, the pressure of which is adjustable. The springs are in cases that are secured to the main carriage by bolts, and the pressure of the springs 70 is regulated by the sleeves *m³* and *m²*, threaded into the casings. The main carriage *D* is always held in its proper relative position to the grinding-stone determined by the conical roller *I*, which is held against it by a pressure 75 due to the weight *h²* on the lever *H*, which is always greater than the pressure on the springs. The details of construction of the springs and their casings are shown in sectional view Fig. 7. The heads of the bolts 80 *m³*, which limit the movement of plate *M*, are countersunk into the said plate *M*. The end of the plate *M* where the cross-carriage strikes it is beveled off to more readily guide the roller. The tendency of the carriage is to 85 force the plate back slightly when the parts are in position (shown in Fig. 3) and then maintain it until the section has been ground. The requisite amount of grinding is predetermined by the adjustment of the lock-nuts *m⁴*. 90

N is a lever having a head which is pivoted eccentrically to the end of the bolt *n*, which in turn is secured to plate *M*. By the operation of this lever the pressure of the springs 95 *m'* upon the carriage is relieved. 100

In order to prevent the trough-like hopper from rising, a bar *V* (shown in full lines, Fig. 1, and in dotted lines, Fig. 2) is so placed as to lie above the carriage-roller *d⁵*.

The main carriage *D* is suitably mounted 105 on rollers *d⁵* and *d⁶*, so as to reduce friction as much as possible.

The pitman is composed of the parts *e³* and *e⁵*, the part *e³* being threaded into the pitman-head *e⁶* and the part *e⁵* threaded into an enlarged portion of the part *e³*. By uncoupling the pitman from either of the wrists it may be lengthened or shortened by turning one part or the other. This adjustment is for the purpose of giving the cross-carriage more or less movement in the direction desired. If small parts are being ground, the travel on the stone may be but little. 115

The operation is as follows: The feeder *C* is pulled back, so as to give room in the hopper for a new supply of sections. The weight *c⁵* then serves to press them forward to the position of being engaged by the chuck of the cross-carriage. With the latter in the position shown in Fig. 7 the section next to be 120 operated upon is pressed by the weight into the position relative to the carriage, shown by dotted lines in Fig. 6. By the rotation of the shaft *E* through the instrumentality of the crank and pitman the cross-carriage is 125 moved in the direction to move the section to be operated upon across the face of the grind- 130

- ing-stone and back. Upon the return movement of the carriage the section is engaged or moves against the plate u^4 and the carriage thus permitted to pass on without it. Thus freed it drops into any convenient receptacle below. Constant action upon the sections gradually wears away the stone and the conical roller wears, in which case the conical roller I is readjusted.
10. What I claim as my invention, and desire to secure by Letters Patent, is—
1. In a grinding-machine, the combination of a main frame, a rotary grinding-stone supported thereon, a supply-hopper, a main carriage provided with devices for automatically moving the blanks to be ground from said hopper and delivering them to the grinding-stone, said main carriage being yieldingly held against the stone and automatically adjustable to compensate for the wearing away of the stone.
  2. In a grinding-machine, the combination of the main frame, a grinding-stone supported thereon, a supply-hopper, a main carriage provided with means for automatically moving the blanks to be ground from the supply-hopper and delivering them to the grinding-stone, racks secured to the main frame, a shaft journaled in said carriage and provided with pinions adapted to engage said racks, and means for turning said shaft.
  3. In a grinding-machine, the combination of a main frame, a grinding-stone supported thereon, a supply-hopper, a main carriage provided with means for automatically moving the parts to be ground from said hopper to the grinding-stone, racks secured to said main frame, a shaft journaled in said carriage and carrying pinions adapted to engage said racks, and a weighted lever having a ratchet-and-pawl connection with said shaft.
  4. In a grinding-machine, the combination of a main frame, a main driving-shaft suitably journaled thereon, a grinding-stone carried by said shaft, a main carriage, a cross-carriage mounted upon said main carriage, a sliding shaft journaled in the main frame and carriage and geared to the main shaft, and a crank-and-pitman connection between the said sliding shaft and cross-carriage, whereby adjustment of the main carriage and cross-carriage relative to the grinding-stone may be made to compensate for wear of the grinding-stone.
  5. In a grinding-machine, the combination of the main frame, a shaft journaled thereon and carrying a grinding-stone, a carriage having means for engaging and moving the blank to be ground across the face of the grinding-stone, and means for adjusting the path of travel of said carriage with relation to the face of the grinding-stone.
  6. In a grinding-machine, the combination of a main frame, a shaft journaled thereon and carrying a grinding-stone, a supply-hopper, a main carriage, a cross-carriage adapted to automatically engage and move the blanks

from the supply-hopper to the grinding-stone, and means movable with the main carriage for actuating the cross-carriage.

7. In a grinding-machine, the combination of a supply-hopper, a carriage, and means to move the blanks to be ground to the discharge end of the hopper to deliver a blank to the carriage as it moves past the hopper, and means to hold the supply away from the discharge end of the hopper on the reverse movement of the carriage.

8. In a grinding-machine, the combination of a grinding-stone, an automatic carriage and a supply-hopper to receive the blanks to be ground, said hopper having an automatically-acting follower adapted to intermittently move the blanks to be ground to position to be engaged by the carriage.

9. In a grinding-machine, the combination of a grinding-stone, a movable carriage for presenting the parts to be ground to the grinding-stone, said carriage adapted to move toward the grinding-stone to compensate for wear, and a roller journaled upon said carriage and adapted to bear upon the grinding-stone to control the position of the carriage relative to said grinding-stone.

10. In a grinding-machine, the combination of a grinding-stone, a carriage adapted to move on a line parallel with the face of the grinding-stone, a chuck in said carriage having a ledge that when moved in one direction shall engage and move the blank to be ground, and when moved in the reverse direction permit the said blank to be forced out.

11. In a grinding-machine, the combination with a grinding-stone, of a carriage provided with a chuck adapted to carry the parts to be ground across the face of the stone, a supply-hopper across the end of which the carriage passes, said hopper being provided with means for holding the supply of blanks away from the carriage to permit the chuck to pass in its backward movement, but to permit it to engage one of the blanks in its forward movement.

12. In a grinding-machine, the combination of a grinding-stone, a cross-carriage adapted to traverse the same and provided with a chuck, and an inclined plate, a supply-hopper having a finger adapted to be operated by said inclined plate on the carriage to move the blanks out of position to permit the chuck to pass said blanks in its backward movement.

13. In a grinding-machine, the combination of a grinding-stone, a carriage to move blanks to be ground across said stone, said carriage being provided with a chuck connected thereto by a joint permitting the blanks to conform to the face of the stone.

14. In a grinding-machine, the combination of a grinding-stone, a carriage adapted to move parts to be ground across the face of the stone, and a chuck secured to the carriage by a universal joint.

15. In a grinding-machine, the combination of a grinding-stone, a carriage movable paral-

lel to the face of the grinding-stone, and yielding devices for holding said carriage in position relative to the face of the stone.

16. In a grinding-machine, the combination 5 of a grinding-stone, a carriage movable parallel to the face of the grinding-stone, and elastically-yielding guides for holding said carriage in position relative to the face of said grinding-stone.

10 17. In a grinding-machine, the combination of a carriage provided with a chuck having supporting-ledges to hold the blank to be ground, a hopper, a bar at the side of the hopper provided with a plate having an inclined and a right-angled edge, whereby the bar is moved by contact of said inclined edge 15 with a blank to permit the blanks to be car-

ried in one direction by the chuck, and to be pushed from the chuck on the reverse movement thereof by the right-angled edge. 20

18. In a grinding-machine, the combination of a grinding-stone, a main carriage movable toward and from said stone, means acting normally to force said carriage toward the stone, a cross-carriage mounted on the main 25 carriage, and means to move it across the face of said stone.

In testimony whereof I affix my signature in presence of two witnesses.

GEORGE W. PACKER.
